DESIGN FOR A SICKLE MOWER

Arvid Stark, Minneapolis, Minn., assignor to Ludwig J. Bratrud, Minneapolis, Minn.

Application July 14, 1939, Serial No. 86,008

Term of patent 14 years

To all whom it may concern:

Be it known that I, Arvid Stark, a citizen of the United States, residing at Minneapolis, county of Hennepin, and State of Minnesota, have invented a new, original, and ornamental Design for a Sickle Mower, of which the following is a specification, reference being had to the accompanying drawings, forming part thereof.

The characteristic feature of my invention resides in the frame shown in solid black lines.

I claim:

The ornamental design for a sickle mower, as shown and described.

ARVID STARK.
